(57) **CLAIM**

The ornamental design for a towel, as shown and described.

DESCRIPTION

FIG. 1 is a front elevational view of the towel in accordance with a first embodiment of the Design;

FIG. 2 is a rear elevational view of the towel of FIG. 1;

FIG. 3 is a front elevational view of the towel in accordance with a second embodiment of the Design; and,

FIG. 4 is a rear elevational view of the towel of FIG. 3.
The ornamental design which is claimed is shown in solid line. The broken lines form no part of the design.
